UNITED STATES PATENT OFFICE.

DANIEL WOODHEAD, OF EVANSTON, ILLINOIS.

LAMP-SOCKET.

1,265,285.

Specification of Letters Patent.

Patented May 7, 1918.

Application filed March 16, 1917, Serial No. 155,312. Renewed February 18, 1918. Serial No. 217,993.

To all whom it may concern:

Be it known that I, DANIEL WOODHEAD, a citizen of the United States, residing at Evanston, in the county of Cook and State 5 of Illinois, have invented a certain new and useful Improvement in Lamp-Sockets, of which the following is a specification.

My invention relates to sockets for electric lamp bulbs, especially locking sockets de-10 signed to prevent unauthorized persons from removing the bulb from the socket. The general object of the invention is to provide a simple and efficient socket of this character. In carrying out my invention, I employ a 15 helical spring into which the threaded lamp base screws. This spring frictionally grips the lamp base when an attempt is made to unscrew it, and the lamp will remain locked in the spring unless the outer end of the 20 spring is held in such manner as to prevent the gripping action. I inclose the spring in a housing which prevents anyone from gaining access to the end of the spring to hold it. I so construct the spring and housing, 25 however, that by a series of proper and quasi secret manipulations on the lamp bulb in the hands of the operator, the housing and spring may be caused to inter-engage and thus hold the spring against performing its 30 gripping and locking function.

I accomplish my object by the construction illustrated in the accompanying drawings, in which:

Figure 1 is an axial section of the lamp 35 socket taken on the line 1—1, Fig. 2.

Fig. 2 is an axial section on the line 2—2, Fig. 1.

Fig. 3 is a view partly in axial section showing the manner in which the prong on 40 the end of the spring may be brought into engagement with the notch or pocket in the housing to permit the lamp to be removed.

Fig. 4 is a transverse section on the line 4—4, Fig. 2.

Fig. 5 is a perspective view of the socket and bulb showing the same in the positions normally occupied when in use.

Fig. 6 is similar to Fig. 5 but shows the prong engaged in the notch or pocket.

Similar numerals refer to similar parts throughout the several views.

In the form selected to illustrate the invention, the socket has a housing 1 of porcelain or other suitable insulating material.

It is fastened to an insulating base 2 by

screws 3, 3, which are suitably connected to supply conductors 4, 5. One of these screws is in electric connection with the center terminal 6, and the other with a shell 7 to which the inner end of a helical spring 8 60 is fastened. Thus, the center terminal 6 and spring 8 are electrically alive and are insulated from each other. When in position in the socket, the center lamp contact 9 engages terminal 6 and the metallic shell 10 65 (which forms the outer contact of the lamp) engages the spring 8. Said spring is also right handed; that is, it progresses inward toward the back of the socket when traced in a clockwise direction. The back of the 70 housing is closed and the housing rather closely surrounds the spring and extends somewhat beyond its outer end.

The outer end of the helical spring has an arm 12 formed upon it. This arm extends outward approximately radially and forms a prong which extends into the annular chamber 13 formed on the inside of the housing. Ordinarily, the different turns of the spring will lie more or less closely together when the lamp base is absent; but screwing the base into the spring will dis-75 tend the latter and move the turns somewhat farther apart. The width of the chamber 13 is great enough to accommodate the 80 prong both when the lamp base is absent and when present. Communicating with chamber 13 at a point remote from the normal position of prong 12 when the lamp base is in place, is a pocket or notch 15 for 85 receiving and retaining the prong.

Commercial lamp bulbs having screw threaded bases are practically all made with right handed threads, so that when the lamp is being screwed into the socket it will be 90 turned in a clockwise direction. Assuming that lamp bulbs having the usual right handed thread on their bases are to be employed, pocket 15 is angularly offset in a clockwise direction from the normal position of prong 12. Furthermore, this pocket is farther from the inner end of the spring than the normal position of the prong. Hence the prong must be rotated in a clockwise direction and also must be pulled out-95ward toward the operator in order to make it enter the pocket.

Operation: It will be understood that when the lamp base is screwed into the spring 8, the latter will frictionally engage 100

it but not sufficiently to grip it and prevent insertion. The right handed coiling of the spring creates a tendency to loosen or enlarge the diameter of the helix when the 5 lamp base is being screwed in. On the same principle the tendency of the spring is to grip the base more and more tightly when an attempt is made to back out the lamp base. And the greater the torsional pressure applied, the greater the gripping action 10 will be so that it is impossible to unscrew the bulb without holding the free end of the spring back and preventing the spring from wrapping itself too tightly around the lamp base. In my device, however, the housing 15 is longer than the spring; that is, it projects outward beyond the point reached by the outer end of the spring. Hence it is impossible for any person to hold back the end 20 of the spring with his fingers or any ordinary tool. Consequently, the lamp is locked in place and is non-removable to all persons except those who know just how to manipulate the device. To the person who is 25 formed, the manner of release is simple. The method is to first rotate the lamp in a clockwise direction; that is, in the direction to screw the lamp farther into the socket. This brings the prong opposite the pocket 30 15, whereupon the operator pulls the lamp toward him and causes the prong to enter the pocket. He then rotates the lamp bulb in an anticlockwise direction, taking care to exert constantly an outward pull to keep 35 the prong in the pocket. He continues this action until the lamp base is finally released. The prong thereupon immediately springs out of the pocket and also swings angularly 40 away from it. Usually the angular distance between the prong and the pocket will be greater when the lamp base is absent than when present, but the parts are so constructed that in any event the prong cannot be brought opposite the pocket without being 45 forcibly rotated through a greater or smaller angle, according to design.

It will be evident from the foregoing that three distinct movements are necessary in order to remove the lamp from the socket. 50 The first movement is to rotate the lamp in the opposite direction to the one finally required to unscrew the lamp. Second, the lamp must be pulled outwardly to seat the prong in the pocket, and third, a reverse 55 rotation must be imparted while the prong continues to be forcibly held in the pocket. Thus with my device, the preliminary movement in removing the lamp is to rotate it in the direction exactly opposite to the one 60 which would be naturally expected. It is very unlikely therefore, that any unauthorized person would accidentally hit upon the program of operation necessary to remove the lamp. It will be noted, also, that 65 it is not sufficient to accidentally bring the

prong momentarily into the pocket. It must be maintained there, against the pressure of the spring, for all or practically all of the time that the lamp is being unscrewed. If the person should at any time permit the 70 prong to leave the pocket, it would be necessary for him to again impart a clockwise rotation and a pull before he can continue the necessary anti-clockwise rotation. And it is not sufficient to merely rotate the lamp 75 in a clockwise direction. The end of the spring itself must be thus rotated and ordinarily if the lamp has been part way unscrewed there will not be sufficient friction between the lamp base and the spring to 80 rotate the spring in a clockwise direction. Consequently, if the operator once lets the prong escape from the pocket he cannot get it back in again without screwing the lamp base back in again, either to the limit or until it creates enough friction to enable it 85 to force the prong back again to the pocket. The device, therefore, requires not only a moderate amount of skill in manipulation, but at least one or two of the three separate 90 motions required are unnatural and therefore unexpected, and therefore not likely to occur to the average person.

In the accompanying drawings, especially Figs. 5 and 6, I have, in order to better explain the principle of operation, shown the housing somewhat wider at the mouth than it is in practice. In the commercial construction, the housing approaches more closely to the lamp base and, being opaque, 95 effectually hides the prong and pocket, at least to an extent sufficient to prevent the proper method from becoming apparent. It is obvious, of course, that the housing may be made quite close fitting and may be 100 lengthened to such an extent as to render the vital parts of the device invisible. 105

Having thus described my invention, what I claim as new and desire to secure by Letters Patent, is:—

1. A socket for electric bulbs having a housing and a helical gripping spring in said housing into which the base screws, the inner end of the spring being fixed, and the housing having a shoulder for engaging the free outer end of the spring to permit unscrewing of the bulb, the shoulder being nearer the mouth of the housing than the free end of the spring is when the bulb is in place, whereby the operator must pull on the bulb and stretch the spring axially before the end of the spring will engage the shoulder.

2. A device of the character described having a socket, a helical spring therein fastened at the inner end to the socket, said spring being adapted to have the base of an electric bulb screwed into it, and a shoulder formed in said socket for engaging the free end of the spring, said shoulder being both 120 125 130

angularly and axially remote from the position which the free end of the spring normally occupies when the bulb is in place.

3. A lamp socket having a housing, a coiled spring therein into which the lamp base screws, the inner end of the spring being fast in the housing and the outer end having a prong, and a pocket in the housing for engaging said prong, said prong being normally angularly offset from said pocket whereby the outer end of the spring must be rotated before the prong can be brought into the pocket.

4. A lamp socket having a housing, a helical gripping spring therein into which the lamp base screws, the inner end of the spring being fast in the housing and the outer end having an arm projecting outward, approximately radially, the spring being distended by the lamp base when the latter is in position, the housing having a pocket for receiving said arm, said pocket being angularly at the left of the normal position of said arm when the lamp base is in position, whereby the operator must, to bring the arm into the pocket, first turn the lamp base a short distance to the left or in the same direction that he would in screwing the lamp base into the housing.

5. A lamp socket having a housing, a coiled spring in said housing into which the lamp base screws, the inner end of the spring being fastened in the housing and the outer end having a projection, the housing having a pocket for engaging said projection to prevent the spring from gripping the lamp base and preventing removal thereof, the pocket being farther from the inner end of the spring than the projection normally is, whereby the operator must pull outwardly to bring the projection into the pocket.

6. A lamp socket having a helical grip-

ping spring into which the lamp base screws, a housing containing said spring and projecting beyond the outer end thereof, a prong on the outer end of the spring, the housing having an internal pocket for receiving and engaging said prong, the pocket being angularly offset and farther out than the normal position of the prong, whereby the operator must both rotate the prong and pull outwardly to bring the prong into the pocket.

7. A lamp socket having a helical gripping spring into which the lamp base screws, a housing for said spring, a prong on said spring, and a pocket in said housing, said pocket being angularly offset to the left of the normal position of the spring and being farther from the inner end of the spring than the prong normally is whereby the operator before unscrewing the lamp must first pull on it and rotate it in a clockwise direction as he would in screwing the lamp in.

8. A locking socket for electric bulbs, the socket having a housing closed at the side and inner end, a helical gripping spring in said housing into which the lamp base screws, the inner end of the spring being secured in the housing and the outer end being free, whereby the spring may be distended when the lamp base is screwed into it, the free end of the spring having a prong projecting outward approximately radially and the socket having a chamber on the inside for accommodating the said prong and a notch communicating with said chamber for receiving and engaging said prong, the notch being farther from the inner end of the housing than the prong normally is when the bulb is in place.

In witness whereof, I have hereunto subscribed my name.

DANIEL WOODHEAD.
